AUTOMOBILE WINDSHIELD DEFROSTING UNIT

Terrence R. Lamb, 1917 S. Randolph St., Arlington, Va.

Filed Oct. 19, 1965, Ser. No. 87,593

Term of patent 7 years

(Cl. D14—6)

FIGURE 1 is a front elevation view of the automobile windshield defrosting unit of the present invention;

FIGURE 2 is a top plan view thereof;

FIGURE 3 is a bottom plan view thereof;

FIGURE 4 is a rear elevation view thereof;

FIGURE 5 is one end view thereof; the other end being similar; and

FIGURE 6 is a partial perspective view thereof.

I claim:

The ornamental design for an automobile windshield defrosting unit, as shown and described.
